TRUING APPARATUS FOR CENTERLESS MACHINES

George Crompton, Jr., Framingham, Mass., assignor to Norton Company, Worcester, Mass., a corporation of Massachusetts

Application March 8, 1946, Serial No. 653,221

6 Claims. (Cl. 125—11)

1

The invention relates to truing apparatus for centerless machines, that is for grinding machines and lapping machines, and with regard to its more specific features for truing the feed wheel or wheels whether the regulating wheel or the grinding wheel or both.

One object of the invention is to provide a truing apparatus which can be adjusted for different sizes of work pieces. Another object of the invention is to provide a truing apparatus which will true feed wheels to a perfect shape or more nearly perfect shape. Another object of the invention is to provide truing apparatus which will permit the use of wide wheels such as are desirable, for example, for centerless lapping machines. Another object is to correct the errors of truing in standard centerless machines.

Another object is to provide, in a machine of the character indicated, a simple adjustment scaled to the size of the work pieces for changing the action of the truing point. Another object of the invention is to provide a mechanism whereby a truing diamond can be moved in a straight line or in a slightly curved line. Another object of the invention is to provide a feed wheel to gear perfectly with a given size of work piece at a skew angle to the wheel. Another object is to permit the use of greater angles of skew of a regulating or feed wheel without sacrificing accuracy in grinding or lapping.

Other objects will be in part obvious or in part pointed out hereinafter.

The invention accordingly consists in the features of construction, combinations of elements, and arrangements of parts, as will be exemplified in the structure to be hereinafter described and the scope of the application of which will be indicated in the following claims.

In the accompanying drawings in which is shown one of various possible embodiments of the mechanical features of this invention,

Figure 1 is a plan view of the apparatus.

Figure 2 is a cross sectional view taken on the line 2—2 of Figure 1, the abrasive feed wheel, however, being shown in elevation.

Figure 3 is a front elevation of a modification of the long bar showing an adjustable support therefor whereby the curved surface upon which the follower travels may be adjusted to allow for variations of the position of the work piece in the grinding throat, the supporting boss being shown in section.

Figure 4 is a side elevation of the long bar and adjustable support of Figure 3.

As conducive to a better understanding of the

2

present invention some observations about centerless grinders, the feed wheel thereof, and the truing apparatus therefor will be made. In a centerless grinder set up for through feed grinding the regulating wheel is adjusted so that its axis is at an angle to the axis of the work piece when the work piece is on the work rest. This angle, called the skew angle, imparts a feeding component to the work piece to move it through the grinding throat. It is common practice to set this angle at about five degrees more or less, and extreme angles have been avoided. It is also common practice when setting up the machine for infeed grinding to place the regulating wheel at a small skew angle, for example one degree, to give a slight feeding component to hold the work piece against a stop.

A cylinder will mesh perfectly with another cylinder provided their axes are parallel, and a cone will mesh with another cone or with a cylinder provided their axes are in a plane. But if two cylinders have non-parallel axes they can be made to touch only at a point and similarly for cones or cylinders if their axes are not in a single plane.

If, however, a truing diamond is moved to cut a regulating wheel by moving the diamond in a line skewed to the axis of the regulating wheel by the same amount that the axis of the regulating wheel is skewed to the axis of the work piece, a regulating wheel is produced which appears to mesh with a cylindrical work piece. This is the customary practice and for many grinding operations the results are close enough to perfection for all practical purposes.

But I have been aware for a long time that a perfect regulating or feed wheel is not thereby produced since no allowance or adjustment is made for different sizes of work pieces. Even if an adjustment were made, within the capabilities of the present machine, there still would not be produced a perfect regulating wheel.

To show that regulating wheels as at present tried are not perfect, it should suffice to show that different shapes of regulating wheels are required for different sizes of work pieces. Let us consider all possible sizes of work pieces referring to the diameter. Such sizes of diameters extend from zero to infinity. A cylindrical work piece of zero diameter which of course cannot exist, will mesh perfectly with a regulating wheel trued as above described because the diamond (theoretically) has a point which does the cutting. Even practically this is nearly true because diamonds have sharp polyhedral angles. Of

course the diamond point moves in a straight line and you can lay a straight line along a straight line. It is believed that the regulating wheel thus produced is a hyperboloid which is defined as a hyperbola of revolution revolved about its axis of symmetry.

Considering the other extreme condition, where the diameter of the work piece is infinity, we have a work piece surface which is a plane. Now it is known that a plane will not mesh with a hyperboloid. Therefore it follows that work pieces of finite diameter will mesh with different surfaces depending upon the particular diameter of the particular work piece. In fact, this can be shown graphically.

To true a regulating or feed wheel properly, I move the diamond along a curved surface, which I believe should be a hyperbolic surface, to correct the action of the truing tool. This, according to the present invention, may be done by providing a follower on the truing tool post and a cam of hyperbolic cylindrical surface, and means for adjusting the cam. For example, if we had a work piece of zero diameter the cam would be set so that the follower would move along an element of the hyperbolic cylinder which is of course a straight line. But for work pieces of finite diameter I set the cam at an angle, the larger the work piece the larger the angle, thus causing the follower to move along hyperbolae of varying asymptotic angles.

Two conditions should be pointed out. In the first place while present machines produce very good work pieces it may be desirable to make a lapping machine with very wide wheels, whereupon the error in present machines would be material. Also for fast through feeding or for other purposes, it may be desirable greatly to increase the skew angle. Again the error of present machines would become material. On the other hand, since present machines are commercially useful and since moving the diamond in a curve causes the results to approach perfection for some machines and skew angles it will be sufficient to approximate perfection as by use of a cam having a surface other than a hyperbolic cylinder, for example, having a surface of a right circular cylinder. Furthermore, as it is very clear that some correction is needed, the apparatus according to the invention achieves improved results even though the correcting surface only partly corrects the bad condition whether absolute theoretical perfection is achieved or not. Therefore I should not be confined to the truth of my theories although I believe them to be true.

Referring now to Figure 2 the apparatus of the invention is shown as mounted on a feed slide 10 which, in the case of a grinding machine, may be the regulating wheel feed slide and in the case of a lapping machine may be either the regulating wheel slide or the lapping wheel slide. By the movement of the slide 10 along ways not shown, the wheel is advanced toward and from another wheel for purposes and in manners known to those skilled in the art. Since subject invention deals with truing and shaping of a wheel, the various parts of a complete machine under and beyond the slide 10 need not be shown or described herein.

Referring to Figure 2, mounted upon the wheel slide 10 is a wheel head 11 which has a flat surface 12. The wheel head 11 is fastened to the slide 10 as by means of bolts 12a. Inside the wheel head 11 is a boss 13 which has a bore

in which is mounted a trunnion shaft 14. The trunnion shaft 14 extends through a yoke 15 and journals the yoke for angular adjustment. To the right of the trunnion shaft 14 is a tightening bolt 16 having a screw threaded part 17 which fits in a threaded bore 18 of the trunnion shaft 14. The tightening bolt has a portion of larger diameter than the bore in which is located the trunnion shaft 14 which leaves a shoulder 19 engaging washers 20 which thrust against the boss 13. The bolt 16 has a square head 21 so that it may be turned with a wrench and when this is done, a head 22 having a conical surface 23 is drawn against a conical seat 24 at one end 15 of the bore in the yoke 15 through which the trunnion shaft 14 passes, and thereby the trunnion is tightened. Accurate centering is obtained by provision of the conical surface 23 and the conical seat 24.

Referring now to Figures 1 and 2 tightening bolts 25 extend through elongated arcuate slots 26 in an arcuate flange 27 which extends upwardly from the wheel head 11. These bolts 25 extend into screw threaded holes provided in the yoke 15. The yoke 15 has a flat surface 30 which is against the flat surface 12 of the head 11. By loosening the bolts 25 and possibly also the bolt 16 slightly, the yoke 15 is free to be adjusted angularly on the trunnion shaft 14 to an amount allowed by the length of the slots 26 which may be up to ten degrees either way or sometimes more. This adjustment may be made with a lead hammer, and a scale and a lubber line, not shown, are provided, one on the wheel head 11 and the other on the yoke 15 so that the adjustment may be accurately made. After the adjustment to the desired skew angle has been made, the bolt 16 and the bolts 25 are tightened and this locks the yoke 15 to the wheel head 11.

The yoke 15 has yoke arms 35 which extend to the left of the base 36 of the yoke. Bearings for a wheel spindle 37 are formed half in the undersides of the arms 35 and half in bearing blocks 38 which are removably bolted to the arms 35 by means of bolts 39. A wheel 40 is the wheel which is to be shaped or trued in accordance with this invention. This wheel 40 may be a feed wheel otherwise termed a regulating wheel or a control wheel, and it may additionally have the function of a lapping wheel or a grinding wheel. It may be made of various materials which can be cut or formed by a truing tool such as a diamond, but in a typical case and preferably it is an abrasive wheel made of abrasive grain such as silicon carbide or fused alumina, bonded with a suitable bond such as vitrified bond, phenolic resin, rubber, shellac, etc. Preferably for such a wheel fine grit abrasive is used bonded with rubber or synthetic rubber or phenolic resin. This wheel 40 is mounted in any usual manner upon the wheel spindle 37, being desirably provided with bushing plates 41 and nuts 42 which also act as spacers.

The wheel spindle 37 may be driven in any usual or desired manner. Preferably some kind of speed changing mechanism is provided in order that the wheel may be driven at various regulating speeds and also at high speeds for truing. Such driving and speed changing mechanism may be mounted upon the wheel slide 10 but is not shown herein. The power may be transmitted through flexible belts to a pulley 45 secured to the wheel spindle 37. Such flexible belts will allow skewing of the yoke 15 without interfering with the drive.

Extending between the yoke arms 35 at the upper, outer corners thereof is a bridge portion 46 which may be cast integral with the remainder of the yoke 15. Formed both in the base portion 36 and the bridge portion 46 of the yoke 15 are ways 51. These ways are curved and form part of a circle. Their surfaces are portions of the inside of a cone. Complementary and therefore exterior conical surfaces 48 (see Figure 1) are formed on the underside of a large table 49 which has a long slot 50 of substantially parallel-epipodal shape which is located in a mid position of the table 49, which is likewise for the most part a rectangular parallelepiped. However, the upper portion of table 49 has dove tail ways 51 fitting which are dove tails 52 on the underside of a slide 53. The slide 53 has a threaded bore 54 extending through it on one side, the axis of the bore being parallel to the ways 51. A screw shaft 55 extends through the threaded bore 54 and is journaled in a boss 56 extending upwardly from the table 49. Collars 57 and 58 hold the screw shaft 55 from axial movement. A hand wheel 60 fastened to the screw shaft 55 is used to rotate it manually and when this is done the slide 53 will be moved slowly along the ways 51. The path of movement of the slide 53 may, however, be altered with respect to the axis of the wheel 40 by adjusting the table 49 on the circular ways 47. In this manner the skew angle of the truing device is established. A scale and a rubber line, not shown, are preferably provided, one on the table 49 and the other on some part of the yoke 15 adjacent to the table in order that the exact amount of skew may be known. A bolt 62 extending into the underside of the table 49 and through a slot 64 in the bridge portion 46 may be used to hold the skew angle after the table 49 is set. In order that the slide 53 shall move along the table 49 in a perfectly straight line without deviation, there is provided between the dove tail 51 and the adjacent dove tail 52 a gib 65 and a couple of adjustment screws 66 extending part way into the gib.

In the center of the slide 53 is an upstanding cylindrical boss 70. In this boss and extending through the slide 53 is a bore 71 the axis of which is perpendicular to the plane of the ways 51 and generally perpendicular to the axis of the spindle 37. In this bore 71 is a shaft 72 the major portion of which closely fits the bore 71. However a lower portion 73 of the shaft 72 is shown of reduced diameter which is a mere matter of clearance and dimensions and in this respect many changes might be made. The lower end of the reduced portion 73 of the shaft 72 is split in a manner not shown herein since it is well known in the art and is illustrated in Figure 9 of Patent No. 1,871,504 to Einstein and Nenninger. In the manner shown in that patent the shaft 72 adjustably holds a slide 80 provided with a scale 81 and secured to the slide 80 is a diamond nib 82 in which is set a diamond 83 with a sharp polyhedral angle. When the zero mark of the scale 81 is opposite some fixed point of the shaft 72, for example, the left hand side of the reduced portion 73, the apex of the diamond 83 is right on the axis of the shaft 72. This is the proper setting for truing when the axis of the work piece intersects a line extending from the exact central point of one wheel to the exact central point of the other wheel. When the work piece is above or below this position, the slide 80 is adjusted in a manner known to those skilled in the art. Briefly the amount of offset of the diamond 83

5 equals the distance of the center of the work above or below the line referred to. The basic reason is that if the work is above or below the line the wheel 40, if at a skew angle, must be bigger at one end than at the other. When the adjustment has been made the split parts of the shaft 72 are clamped together by a bolt 84 to hold the slide 80 firmly. To prevent the shaft 72 from turning there is provided a spline 86 therein in which fits a key 87 which also extends into a key seat in the boss 70.

6 Referring to Figure 1 as well as Figure 2 a holding member 90 has a split bore 91 fitting the shaft 72. Arms 92 extend on either side of the split and a bolt 93 passes through them. A nut 94 on the bolt 93 may be tightened thus to draw the arms 92 together and clamp the member 90 securely to the shaft 72 in a desired position of adjustment. The member 90 has a screw threaded bore 96 parallel to the split bore 91. In this screw threaded bore 96 is a screw shaft 97 the lower end of which has a follower point 98. The hub 99 of a hand wheel 100 is driven onto a tapered portion 101 of the shaft 97 and may be further secured thereto by means of a key 102 fitting in a key way 103 of the shaft 97 and also in a key seat in the hub 99. It will be clear that when the hand wheel 100 is turned the member 90 will be raised or lowered relative to the shaft 97. This action raises or lowers the diamond 83. The follower point 98 is exactly on the axis of the shaft 97. To lock the shaft 97 to the member 90 I provide a knurled nut 104 on the shaft 97.

The follower point 98 rests on the curved surface 110 of a long bar 111 which has an integral shaft 112 extending at right angles to the long bar 111 from its mid position. A conical seat 113 is provided where the long bar 111 and the shaft 112 merge and rests against a conical seat 114 in the upper part of a bore 115 provided in a boss 116 which is formed as an extension of the table 49. The axis of the bore 115 is at all times parallel to the axis of the shaft 72. The long bar 111 may be adjusted to any angular position and when so adjusted may be clamped in this position by means of a screw bolt 117 extending into a threaded bore 118 in the shaft 112 there being a thrust washer 119 between the head of the bolt 117 and the underside of the boss 116. As in the case of other adjustments scale marks and a rubber line (not shown) are provided, one on the upper surface of the boss 116 and the other on the long bar 111. The surface 110 is the surface hereinbefore referred to which may be part of a hyperbolic cylinder or may be a segment of a right circular cylinder.

Although there may be other ways, one method of making a surface which is part of a hyperbolic cylinder is known to me. Take a good surface grinder provided with a magnetic chuck and provide it with a fine grit grinding wheel. Provide a slide mechanism consisting of a base with a slide way, a slide in the slide way and secure a nib with a truing diamond to the slide. The base should be made of iron. Set the wheel spindle straight i. e. perpendicular to the motion of the slide of the surface grinder and horizontal. Place the base of the slide mechanism on the magnetic chuck so that the diamond will move at a slight skew angle to the wheel spindle of the surface grinder. An angle of about five degrees will give good results. Provide a hand screw feed mechanism for the slide of the slide mechanism. Now set the main slide of the surface grinder so that the diamond will move

through the vertical center line of the wheel. Then lower the wheel and true it with the diamond. Then set the long bar 111 in a fixture on the magnetic chuck so that the long dimension of the long bar 111 is parallel to the ways of the surface grinder and so that the center of the long bar 111 is right under the central point of the grinding wheel. Now grind using traverse and downfeed but no cross feed. After the surface 110 has been ground the grinding lines may be removed by careful application of fine grit abrasive paper or cloth.

The axis of the wheel 40 is set to the desired skew angle by adjusting the yoke 15 as described. Let us suppose that this is five degrees. Then the table 49 is set to a skew angle of five degrees. If Figure 2 is a view from the front of the machine the skew of the yoke 15 will be set to raise the front end of the wheel 40. This will cause the work piece to feed through the grinding throat from front to back of machine as is of course desired. But except for the subsequent setting of the slide 80 (which can be set either way) it does not matter in which direction you skew the table 49 so long as the amount is the same as the skew of the yoke 15. Now the slide 80 is set for work piece above or below the center line, the work piece usually being above. Which way to set the slide 80 depends on the other settings and is well known to those skilled in the art so no detailed rule will be given. Now the long bar 111 is skewed by an amount depending upon the size of the work piece, increasing for increasing sizes of work piece. A table of skew angles for the bar 111 with coordinates of skew angles of the yoke 15 and of work piece sizes will be provided. This table can be derived by mathematics.

The above settings having been made and the wheel 40 set in rotation at a high rate of speed, the hand wheel 100 is turned to bring the diamond 83 over one edge of the wheel 40. It is assumed that the diamond 83 was not low enough to make contact. Now the knurled nut 104 is backed off and the hand wheel 100 is turned until slight contact is made between the diamond 83 and the wheel 40. From the construction described it will be seen that turning of the hand wheel 100 raises and lowers the diamond 83. The weight of the apparatus will hold the diamond down to some extent, but a spring 120 extending from the bolt 93 to an eye bolt 121 in the slide 80 may be provided to assure firm contact between the diamond 83 and the wheel 40. Further instructions about operation are superfluous since the manner of using the apparatus will now be clear to those skilled in the art. The knurled nut 104 is tightened between adjustments and truing should be gradually accomplished to avoid burning the diamond 83 and to achieve a true shaped surface on the wheel 40.

When the long bar 111 is set at zero skew, the follower 98 travels along a line which is the generatrix of the hyperbolic cylinder when it is at the vertex of the directrix hyperbola. This is a straight line and under such conditions the wheel 40 will be trued exactly the same as in conventional centerless grinders and with the same results. When, however, the long bar 111 is set to any skew angle, the follower will trace a hyperbola, the less the angle, the flatter the hyperbola. The limiting hyperbola is the directrix hyperbola which is reached when the skew angle of the long bar 111 is set at 90°. Of course a skew angle of 180° is the same as a skew angle of 0° and a skew

angle of 270° is the same as a skew angle of 90°.

However it is desirable to make still another adjustment. To understand this it is appropriate to consider the truing action from a general point of view. The diamond 83 when it moves along a skew angle to the wheel 40 digs deeper into the wheel as it moves towards the center of the wheel from one edge. It will dig deepest at the center plane of the wheel only when the slide 80 is set at zero. Now the follower 98 should ride over the vertex generatrix when the diamond 83 digs deepest into the wheel 40 (i. e. is nearest to the axis of the wheel 40). When this condition is achieved the compensation will be symmetrical to the action, i. e. the hyperbolic compensation of this invention will be symmetrical to the hyperbolic truing of the old art.

Referring now to Figures 3 and 4, I provide a long bar 111a with a hyperbolic cylindrical surface the same as already described. Integral with the long bar 111a is a dove tail 125 which fits in a clamping member 126, the clamping member 126 constituting ways for the dove tail member 125 whereby it may be moved perpendicularly to the long dimension of the long bar 111a. The clamping member 126 is an integral part of a shaft 112a just like the shaft 112 and having a conical seat 113a which rests in the conical seat 114 of the boss 116. Screws 127 are provided to clamp the dove tail 125 in the adjusted position and a fine scale and a lubber line (not shown) are provided, one on the dove tail 125 and the other on the member 126 to determine the adjustment. These may be read with a magnifying glass. The setting should be such that when the diamond 83 is nearest to the axis of the wheel 37, the follower 98 is on the vertex generatrix of the surface 110.

To recapitulate the settings, first the yoke 15 is skewed to the desired amount and there are tables of rate of feed of work pieces for sizes and R. P. M. of wheels and skew angles. Next the table 49 is set to the same skew angle. Thirdly the slide 80 is set for work piece above or below the center line of the wheels and in a direction dependent on whether above or below and in which direction the table 49 was skewed. All of this is as usual and is known to the art.

Now the angular skew of the long bar 111 or 111a is set according to table in which the diameter of the work piece is one entry and the skew of the table 49 is another entry. Now another table is provided for the adjustment of the dove tail 125 in the clamping member 126 in which the position of the slide 80 by the scale 21 is one entry and the skew angle of long bar 111a is the other entry. This table can be made from mathematics and is based upon the particular hyperbola of the directrix of the surface 110.

There is one remaining point. If the settings which are old in the art were made so that the far end of the wheel 37 will be larger than the near end to correspond with work piece above the center line, and the skew of the long bar 111a is clockwise in plan view, the dove tail 125 is moved to the right. For extreme settings of the slide 80 the follower 98 may be always to one side of the vertex generatrix.

It will thus be seen that there has been provided by this invention an apparatus in which the various objects hereinabove set forth together with many thoroughly practical advantages are successfully achieved.

As many possible embodiments may be made of the above invention and as many changes

might be made in the embodiment above set forth, it is to be understood that all matter hereinbefore set forth or shown in the accompanying drawings is to be interpreted as illustrative and not in a limiting sense.

I claim:

1. In a truing apparatus having a spindle for the wheel to be trued, a truing diamond, means including a slideway and a slide thereon for moving said diamond rectilinearly, angularly adjustable skew means whereby the slide will move the diamond parallel to the axis of the spindle or at a skew angle thereto, a mounting for the diamond in the slide whereby the diamond can move towards or away from the spindle as the slide moves, and a follower having a point, the combination with said truing apparatus of a template member for said follower having a surface generated from a straight line moving along a curve as directrix, one of the last two parts being connected to the mounting for the diamond and the other stationary with respect to the slideway but adjustable angularly relative thereto, whereby the diamond moves in and out as the follower follows the surface to correct the truing.

2. In a truing apparatus having a spindle for a wheel to be trued, a slideway, skew means to adjust the slideway angularly relative to the axis of the spindle, a slide on the slideway, and a truing member mounted on the slide and having a truing point, the member being mounted for movement of the truing point towards and away from the axis of the spindle, the combination with said truing apparatus of means for giving the point a slight movement in the direction towards and away from the said axis as the slide moves, said last named means comprising a pointed member and a curved surface, one connected to the truing member and the other to the slideway, the surface being angularly adjustable and being a hyperbolic cylinder.

3. In a truing apparatus having a spindle for a wheel to be trued, a truing tool, means to move the truing tool at a skew angle to the spindle, and a mounting for the truing tool permitting it to move towards and from the spindle as it is moved at the skew angle, the combination with said truing apparatus of means including a follower and a surface to cause said truing tool to move towards and from the spindle as it is moved, said surface being a hyperbolic cylinder so that the truing tool moves in a hyperbolic path.

4. In apparatus as claimed in claim 3, the com-

bination with the parts and features therein specified, of an adjustment whereby any one of an infinite number of hyperbolic paths may be selected.

5. In a truing apparatus having a spindle for the wheel to be trued, a truing tool, means for moving the truing tool in a path which makes a skew angle to the axis of the spindle, and a mounting permitting movement of the truing tool transverse to said path so that the tool may approach and recede from said axis, the combination with said truing apparatus of means for moving said truing tool transversely as it moves in said skew path comprising a part having a fol-
10 lower point, a part having a surface generated by moving a straight line along a curve as directrix, one of said parts being connected to said tool and the other being stationary with respect to said tool as it moves, and means for angularly ad-
15 justing said surface with respect to said path.
6. In a truing apparatus having a spindle for the wheel to be trued, a truing tool, means for moving the truing tool in a path which makes a skew angle to the axis of the spindle, and a mounting
20 permitting movement of the truing tool trans-
verse to said path so that the tool may approach and recede from said axis, the combination with said apparatus of means for moving said truing tool transversely as it moves in said skew path comprising a part having a follower point, a part
25 having a surface generated by moving a straight line along a curve as directrix, one of said parts being connected to said tool and the other being stationary with respect to said tool as it moves,
30 means for angularly adjusting said surface with respect to said part, and a transverse adjustment for one part with respect to the other part to se-
35 lect different paths on the surface for said fol-
lower point.
